[57] CLAIM

The ornamental design for a combined garment bag and overnight case, as shown and described.

DESCRIPTION

FIG. 1 is a side elevational view of a combined garment bag and overnight case showing my new design in the folded assembled condition for carrying;

FIG. 2 is a side elevational view of the other side of the combination cases as shown in FIG. 1 but with the shoulder strap omitted;

FIG. 3 is an end view of one end of the combination cases as shown in FIG. 1 but with the shoulder strap omitted;

FIG. 4 is an end view of the other end of the combination cases as shown in FIG. 1 but with the shoulder strap omitted;

FIG. 5 is a top plan view of the combination cases as shown in FIG. 1 but with the shoulder strap omitted;

FIG. 6 is a bottom plan view of the combination cases as shown in FIG. 1;

FIG. 7 is a side elevational view of one side of the garment bag portion of the combined garment bag and overnight case when same is separated from the combination shown in FIGS. 1-6, the garment bag being shown in a hang-up position with the shoulder strap omitted;

FIG. 8 is a side elevational view of the other side of the garment bag portion as shown in FIG. 7;

FIG. 9 is a top plan view of the garment bag position shown in FIG. 7, but with the shoulder strap omitted;

FIG. 10 is a bottom plan view of the garment bag portion shown in FIG. 7;

FIG. 11 is an end view of one end of the garment bag portion shown in FIG. 7;

FIG. 12 is an end view of the other end of the garment bag portion shown in FIG. 7;

FIG. 13 is a side elevational view of one side of the

garment bag portion of the combined garment bag and overnight case when same is separated from the combination shown in FIGS. 1-6, the garment bag being shown in a fold up or carrying position with the shoulder strap connected thereto;

FIG. 14 is a side elevational view of the other side of the garment bag portion as shown in FIG. 13, but with the shoulder strap broken away;

FIG. 15 is a top plan view of the garment bag portion shown in FIG. 13, but with the shoulder strap broken away;

FIG. 16 is a bottom plan view of the garment bag portion shown in FIG. 13;

FIG. 17 is an end view of one end of the garment bag portion as shown in FIG. 13;

FIG. 18 is an end view of the other end of the garment bag portion as shown in FIG. 13;

FIG. 19 is a side elevational view of one side of the overnight case portion of the combined garment bag and overnight case when same is separated from the combination shown in FIGS. 1-6, the overnight case being shown with the shoulder strap connected thereto; FIG. 20 is a side elevational view of the other side of the overnight case portion as shown in FIG. 19, but with the shoulder strap omitted;

FIG. 21 is a top plan view of the overnight case portion shown in FIG. 19, but with the shoulder strap omitted; FIG. 22 is a bottom plan view of the overnight case portion shown in FIG. 19; and

FIG. 23 is an end view of one end of the overnight case portion shown in FIG. 19, but with the shoulder strap broken away, the other end of the overnight case portion being a mirror image thereof.
